UNITED STATES PATENT OFFICE

162,103

ROSARY

Kathleen M. Wilson, Oakland, Calif.

Application December 31, 1949, Serial No. 6,946

Term of patent 7 years

(Cl. D45—16)

To all whom it may concern:

Be it known that I, Kathleen M. Wilson, a citizen of the United States and a resident of Oakland, Alameda County, California, have invented a new, original, and ornamental Design for a Rosary, of which the following is a specification, reference being had to the accompanying drawing, forming part thereof.

Figure 1 is a front elevational view of a rosary showing my new design, the back of the connecting medallion being the same in appearance as the front.

Figure 2 is a side elevational view of the rosary as shown in Figure 1; and

Figure 3 is a top plan view thereof.

My design for a rosary is characterized by the large connecting medallion in association with the plain cross, the diameter of the connecting medallion being substantially equal to the length of the cross.

I claim:

The ornamental design for a rosary, substantially as shown and described.

KATHLEEN M. WILSON.
